CLAIM

The ornamental design for a lighting assembly, as shown and described.

DESCRIPTION

FIG. 1 is a perspective, front view of a lighting assembly according to one embodiment.

FIG. 2 is a front view of the lighting assembly of FIG. 1. FIG. 3 is a back view of the lighting assembly of FIG. 1. FIG. 4 is a left side view of the lighting assembly of FIG. 1. FIG. 5 is a right side view of the lighting assembly of FIG. 1.

FIG. 6 is a top view of the lighting assembly of FIG. 1; and, FIG. 7 is a bottom view of the lighting assembly of FIG. 1. The broken lines shown represent unclaimed subject matter and form no part of the claimed design.
